CLOSURE

Geno Lesti, Cleveland, Ohio

Application August 31, 1935, Serial No. 38,837

6 Claims. (CL. 150—3)

This invention relates to closures and more particularly to a sealable container and the method of its manufacture.

In the past various constructions for sealable containers of the class formed of flexible, waterproof sheet material and the like, have been developed that have had clamping means, rolled edge means and the like, for sealing the mouth portions of the containers to prevent water and air from passing therethru. Most of the constructions that have been developed heretofore have been so involved in operation or so cumbersome in structure that they have failed of general commercial acceptance.

15 An object of the present invention is to provide a molded waterproof container that has a positively sealing closure means that effectually seals the mouth of the container against the passage of air or water therethru and that is simply and easily operated to provide access into the interior of the container.

20 Another object is to provide a bathing trunk pouch for the retention of cigarettes, matches and the like, that may be immersed in water for a prolonged period of time without the entrance of water into the interior thereof.

25 Another object is to provide a container or pouch for the retention of articles from which water and air are to be excluded that is of simple and inexpensive manufacture.

30 With the above and other objects in view, which will be apparent to those skilled in the art to which the present invention pertains from the following description, the present invention comprises a waterproof container that is illustrated by a waterproof bathing trunk pouch as shown in the accompanying drawing, wherein:

35 Fig. 1 is an elevational view of the bathing trunk pouch with an upwardly opening mouth that is provided with the preferred form of pouch mouth sealing means;

40 Fig. 2 is a section taken along the line 2—2 of Fig. 1;

45 Fig. 3 is an enlarged detail section of the upper portion of Fig. 2;

Fig. 4 is an enlarged detail plan view of one end of the closed pouch mouth;

Fig. 5 is an enlarged detail section partly broken away, taken along the line 5—5 of Fig. 4;

50 Fig. 6 is an elevation that shows the pouch mouth positioned transversely of the pouch face for the purpose of improved drainage;

55 Fig. 7 is an elevation that shows the pouch mouth positioned along a lateral edge of the pouch for the purpose of improved drainage;

Fig. 8 is an enlarged section of one modified form of pouch mouth seal construction wherein the mouth sealing means is disposed inwardly of the fastener means;

Fig. 9 is an enlarged section of a second modified form of pouch mouth seal construction wherein the mouth sealing means is disposed outwardly of the fastener means; and

Fig. 10 is a section taken along the line 10—10 of Fig. 9.

The container or pouch that embodies the present invention comprises a hollow, preferably continuously homogeneous body portion of resilient rubber that is molded to form a single piece construction that comprises the side walls 1, the bottom edge wall 2, the lateral edge walls 3, the belt loops 4 thru which the bathing trunk belt 5 may be passed, and the plurality of outer and inner pairs of pouch mouth portions 6 and 7 respectively. The pairs of pouch mouth portions 6 and 7 are separated longitudinally by slots for the reception, preferably by assembly, of the rubber impregnated fabric stringers 8 that carry the conventional interengageable slide fastener interlocking elements 9. The fabric stringers 8 are firmly secured within the slots in the pouch mouth portions 6 and 7 in any suitable manner, as by vulcanization, or by the use of rubber cement. The slider 10 causes the engagement or the disengagement of the interlocking elements 9 as the pull tab 11 is moved longitudinally of the pouch mouth.

The heavy shoulder constructions of the pairs of pouch mouth portions 6 and 7 provide ample thrust strength to uniformly and strongly compress the opposed pairs of contact faces 12 and 13, respectively, thereof, as the interlocking fastener elements 9 are progressively interengaged by the operation of the slider 10. The individual contact faces that comprise each contacting pair when disengaged preferably incline slightly toward each other away from the slide fastener elements in section, as shown emphasized in dotted outline.

The slider stem portion 14 that is interposed between the slider 10 and the pull tab 11 is preferably shaped in transverse section so that it substantially converges in conformity with the convergence of the pair of contact faces 12 of the pair of outer pouch mouth portions 6 between which it passes in frictional engagement as the slider is moved longitudinally of the pouch mouth. The sectional contour of the stem 14 preferably reduces to a minimum the size of the apertures between the stem 14 and the pair of contact

faces 12 of the pair of outer pouch mouth portions 6 in which water drops might be retained and also minimizes the tendency of the pair of contact faces 12 of the outer pouch mouth portions 6 to become pitted from frictional wear. The section of the stem 14 that is shown in Fig. 4 as being substantially wedge-shaped may be replaced with a stem, both of the edges of which converge symmetrically from the middle of the stem in close conformity with the curvature of the contact faces 12 of the outer pouch mouth portions 6, somewhat as is shown in Fig. 10 of the drawing, if desired.

The inner pouch mouth portions 7 are preferably continuous at either end with a longitudinally extending slider underlying portion 15 that is continuous with the pouch side walls 1 transversely of the pouch and with the lateral edge walls 3 longitudinally of the pouch. The slider 20 underlying pouch portions 15 preferably contain the stiffening reinforcing members 16 permanently embedded therein that maintain the surface of the portions 15 level so that the slider 18 in its extreme positions may be smoothly positioned wholly above the portions 15.

This construction provides, in the closed position of the pouch mouth, a continuous, uniformly compressed engagement throughout their lengths, of the contacting faces 12 and 13 of the pouch mouth portions 6 and 7 respectively, with the slider 18 disposed wholly above the slider underlying pouch portion 15. The ends of the pouch mouth may be open as shown in Figs. 4 and 5, or may be closed as shown in Fig. 10, which is the more desirable construction.

The pull tab 11 may be joined to the slider 18 rigidly as shown, or, if desired, it may be hingedly connected thereto in any of the several conventional styles. A slider retaining clasp, not shown, may also be provided for holding the slider 18 in its fully closed position by any of the accepted conventional constructions, if desired.

The sealing closure means may, if desired, be positioned in various relations with respect to the pouch to improve the drainage of water from the closure means prior to the opening of the mouth of the pouch, such as its being positioned in the face of the pouch at an inclined angle with the edges thereof, as is shown in Fig. 6, or along a side edge of the pouch, as is shown in Fig. 7 of the drawing.

A modified form of the sealing closure means is shown in Fig. 8 of the drawing, wherein the sealing means is disposed wholly beneath the slide fastener securing means.

In this construction the heavily shouldered pouch mouth portions 17 have opposed contact faces 18 that incline slightly toward each other in cross section away from the slide fastener when not in secured position, as shown in dotted outline, to provide a tight, uniform contact pressure on the interengagement of the interlocking elements 8 as the slider 18 is drawn longitudinally of the pouch mouth by the operation of the pull tab 11. The interlocking element carrying stringers 8 are permanently secured in stringer receiving grooves that extend longitudinally of the shoulder pouch mouth portions 17 in a suitable manner, as by vulcanization or by the use of cement.

A second modification of the closure means is shown in Fig. 9 of the drawing, wherein the sealing means is disposed wholly outwardly of the slide fastener securing elements.

In this construction the opposed shoulder pouch

mouth portions 19 carry the hookless fastener stringers 6 embedded therein securely and have contact faces 20 that engage each other in strongly compressed relation. The contact faces 20 preferably slightly incline toward each other in cross section away from the hookless fastener securing means when in released position shown emphasized in dotted outlines to provide a uniform, tight contact therebetween when the hookless fastener elements 8 are in secured engagement. The interlocking hookless fastener elements 8 are slidably engaged by the slider 21 that is joined to the pull tab 22 by the stem 23 that is preferably of thin, streamlined cross section, as shown in Fig. 10. The stem 23 is preferably tapered in transverse section in both directions in order that the presence of apertures between its sides and the contact faces 20 may be minimized. The reinforcing means 24 is disposed at either end of the pouch mouth and arrests the motion of the stem 23 longitudinally thereof.

The preferred method of manufacturing the pouch comprises a single molding operation whereby no seams open from inwardly of the pouch to the exterior thereof with the exception of the mouth portion opening, thereby providing a construction that is substantially intact against the transfer of air or water thru the walls of the pouch.

It is to be understood that the particular embodiments of the invention that are shown and described herein are shown for purposes of illustration and explanation, and that various modifications in the materials, the shapes, the mode of assembly and the adaptations that are shown and described, may be made without departing from the invention as defined in the appended claims.

What I claim is:

1. A waterproof closure, comprising a rubber body portion having a mouth, a pair of opposed shoulder members structurally continuous with said body portion and defining the mouth for said body portion, shoulder member contact faces in transversely angularly opposed relation with each other, closure mouth closing means, and means slidably disposed between said contact faces in substantially water sealing relation therewith for operating said closure mouth closing means.

2. A container closure, comprising a pair of transversely compressible and heavy and releasably contacting shoulder members, slide fastener stringers anchored within said shoulder members and extending longitudinally thereof, a plurality of slide fastener elements carried by said stringers, contact faces forming releasably contacting parts of said shoulder members and inclining toward each other transversely of said shoulder members away from said slide fastener elements, a slide fastener slider for causing the engagement and the release of said slide fastener elements and the compressing contact of said pairs of contact faces of said shoulder members in uniformly graduated magnitude away from said slide fastener elements, and a slider stem portion of substantially oval section disposed between said pair of shoulder member contact faces in substantially water and air sealing engagement therewith throughout its travel.

3. A container closure, comprising transversely heavy and opposed shoulder members of resilient rubber, compression contact shoulder member faces in angular relation with each other transversely of said shoulder members and symmetrically supported throughout their wide areas of con-

tact by said heavy shoulder members, slide fastener stringers securely anchored within said shoulder members and extending longitudinally thereof, a plurality of interengaging slide fastener elements carried by said stringer members, a slider for successively causing the interengagement and the release of said slide fastener elements, and a pull tab for operating said slider.

4. A container closure, comprising transversely opposed heavy and thick shoulder members of resilient rubber composition, compression contact shoulder member faces substantially continuously contacting each other in pairs transversely angular of said shoulder members and in uniformly increasingly compressing relation toward one edge thereof, slide fastener stringers securely anchored within said shoulder portions, a plurality of interlocking slide fastener elements carried by said stringers, a slider for successively causing the interengagement and the release of said elements, a pull tab for operating said slider and accessible externally of said closure, and a slider stem portion of substantially streamlined transverse section interposed between and

operatively connecting said slider with said pull tab and disposed between one pair of said compression faces in substantially water sealing relation therewith.

5. A closure mouth aperture that is releasably sealable with respect to air and water, comprising a plurality of compressible and thick shoulder mouth portions defining said closure mouth aperture, closure mouth aperture closure means, and contact faces forming parts of said mouth portions and transversely engaging each other in pairs in increasingly compressing closure mouth sealing engagement away from said mouth aperture closing means when closed and inclining toward each other away from said mouth aperture closing means when in released position.

6. A container closure, comprising rubber strips forming a closure mouth, closure means for engaging said rubber strips in opposed compressing relation, and said rubber strips engaging each other in surfaces that incline toward each other transversely thereof and away from said closure means.

GENO LESTI.
